MIXING CHAMBER

Howard Kent, Maplewood, N. J., assignor of one-half to J. Vincent Volk, Newark, N. J.

Application November 30, 1949, Serial No. 130,302

1 Claim. (Cl. 210—36)

1

My invention relates generally to mixing chambers and specifically to mixing chambers in which soap, detergents, or other materials are picked up by a fluid passing through.

It is among the objects of my invention to conduct a fluid into a mixing chamber, disperse it in the presence of another material, so that it may become thoroughly involved with or take up that material and then conduct some of the material out of the chamber without interfering with the balance of the material remaining behind, or it may leave behind part of its contents.

It is another object of my invention to provide a labyrinth through which a fluid may be conducted and discharged after it has taken up a quantity of other material, or left behind a part of its contents.

Yet another object of my invention is to provide a repository for a quantity of material which will bring it in contact with a fluid and yet not permit the material to be entirely swept away by the fluid.

Still another object of my invention is to provide a chamber for rapidly mixing material with a fluid whenever the fluid is channeled into the chamber.

It is among the further objects of my invention to provide a mixing chamber which is simple in form, relatively easy to construct and maintain, inexpensive and durable.

These objects and advantages, as well as many other objects and advantages, may be achieved from the device illustrated in the drawings in which:

Figure 1 is a vertical cross-section of the assemblage;

Figure 2 is a side view in perspective;

Figure 3 is a view of the cap;

Figure 4 is a bottom view in perspective of the lid; and

Figure 5 is a side view in perspective of the inner chamber with a wall exploded away.

Referring now to the drawings in detail, my mixing chamber provides an outer chamber 11 and an inner chamber 12. The outer chamber

11 is provided with internal threads 13 at the top. There is a lid 14, for the outer chamber 11, that has a downwardly extending threaded flange 15 which engages with the internal threads 13 of the outer chamber 11. The lid 14 is provided with an entrance port 16. There is an opening 18 in the center of the lid. The entrance port 16 communicates with the opening 18 in the center of the lid 14. The top of this opening 18 is provided with threads 19 to receive a cap 20

2

and the bottom of the opening is likewise provided with threads 21 to receive the inner chamber 12. The lid 14 is also provided with a discharge port 22 by which the contents of the outer chamber 11 are discharged.

There is a cap 20 for the inner chamber 12. The cap is provided with threads 23 to engage the threads 19 of the lid. A suitable washer 24 is used to insure a tight seal. The cap 20 has an annular channel 25 opposite the entrance port 16 of the lid 14. A number of passages 26, 26 extend through the cap 20 and intersect with holes 27 in the bottom of the cap 20.

The inner chamber 12 has an externally threaded lip 28 that engages the thread 21 of the lid 14. The bottom of the inner chamber 12 is provided with a number of holes 29 that provide a passage into the outer chamber 11. An annular recess 30 in the bottom of the lid 14 provides access from the outer chamber 11 to the discharge port 22.

The operation of the mixing chamber is as follows. A detergent, or other material, is disposed in the inner chamber 12. A fluid is conducted through the entrance port 16 into the annular channel 25. From there, it enters the passages 26 and goes out the holes 27, whence it falls on the detergent in the inner chamber 12. The detergent, or other material, is dissolved and the fluid passes out the holes 29 into the outer chamber 11. The fluid then goes into the annular recess 30 and out of the discharge port 22. A washer 31 will seal the lid to the outer chamber 11. This mixing chamber is suitable for use with detergents, antiseptics, water softeners, dyes, and for the purpose of adding any soluble solid to a liquid passing through.

The foregoing description is intended merely as illustrative of one embodiment of my invention for many changes may be made in the construction, selection, and arrangement of the various parts, all within the scope of the appended claim, without departing from the spirit of the invention.

45 I claim:

A mixing chamber for continuously dissolving and mixing solid materials in a liquid flowing therethrough comprising an outer chamber open at one end, a lid attached to the open end of the outer chamber and having a passage therein terminating in a discharge port, and said lid further having a central opening therein, a percolate inner chamber open at one end and positioned within the outer chamber with its open end connected to the opening in the lid, a cap

for the top of the inner chamber attached to the lid and having a passage therein, said lid also having an entrance port communicating with the passage in the cap and the said passage in the cap having a plurality of holes extending to the inner chamber.

HOWARD KENT.
